ROTARY STOCK THICKENER AND REFINER

Edmund P. Arpin, Jr., Neenah, Wis.

Application October 13, 1955, Serial No. 540,278

6 Claims. (Cl. 241—30)

This invention relates to improvements in rotary refining machines which are used to refine wet, fibrous material, such as pulp, paper stock and the like.

The present invention has particular application to a rotary refiner of the type having a cylindrical abrasive liner and a series of rotor elements carried on a central shaft and movable against the abrasive liner by centrifugal force upon rotation of the shaft, the material being moved progressively axially through the machine from an inlet to an outlet as it is treated by the refining surfaces. It has been found that for this type of machine to operate at its highest efficiency there is an optimum stock consistency which is higher than that normally fed to stock refiners. The reason for this is that the water, if above a certain percentage, tends to act as a cushion which prevents the pulp fibers from being most efficiently acted upon by the refining elements of the machine. Also, excess water tends to propel the stock through the machine too rapidly for thorough action. Indications are that under high density conditions, treatment costs on this type of machine are very much reduced from that of any known competitive equipment. It is also possible to provide a wide range of treatment effects under high density stock conditions which are not obtainable at lower densities.

It is thus an important object of the present invention to provide a novel and improved rotary refiner machine having means associated therewith to regulate the density of fibrous material being fed into the refining surfaces.

It is a further object of the present invention to provide such a machine which is extremely simple in construction and which requires a minimum of floor space.

It is another object of the present invention to provide such a machine which will operate with or without a preliminary separate operation removing water from the stock.

It is a further object of the present invention to provide improved means for controlling the amount of water removed from a stock mass prior to a refining action thereon, and to provide a water extracting means which is of optimum construction from the standpoint of accumulated settlement and biological contamination.

Other and further objects, features and advantages of the present invention will be apparent from the following detailed description taken in conjunction with the accompanying drawings, in which:

Figure 1 is a side elevational view of a rotary refiner machine constructed in accordance with the present invention;

Figure 2 is a fragmentary longitudinal sectional view of the inlet end of the machine of Figure 1;

Figure 3 is an enlarged fragmentary transverse sectional view illustrating the means for extracting liquid from the inlet chamber for increasing the consistency of the stock;

Figure 4 is a fragmentary elevational view of the structure of Figure 3;

Figure 5 is an end elevational view of the impeller

2

mechanism at the inlet end of the machine which operates in increasing the consistency of the stock at the inlet end of the machine;

Figure 6 is a fragmentary enlarged sectional view taken generally along the line VI—VI of Figure 5; and

Figure 7 is an elevational view looking in the direction of the arrows VII—VII in Figure 5.

As shown on the drawings:

The present invention is illustrated as being embodied in a rotary refiner machine indicated generally by the reference numeral 10, including a generally cylindrical shell or casing 11 which may be supported in a generally horizontal orientation upon suitable supports 12. The shell 11 is provided with end plates 13 and 14 closing the ends thereof, the end plate at the inlet end of the machine having an inlet pipe 16, and the plate 14 at the discharge end having a discharge pipe 17. A hollow shaft 19, Figure 2, extends axially through the refiner machine and is journaled in suitable bearings 20 and 21 at the opposite ends of the machine. The shaft 19 is adapted to be rotated by means of a grooved pulley (not shown) secured on the shaft externally of the casing 11.

The shell 11 is provided internally with a liner 22, Figure 2, composed of a number of ring sections 23 which are formed of suitable abrasive material, such as stone, metal or synthetic ceramic of an abrasive type. A series of equally spaced helical grooves (not shown) extend longitudinally in the machine and form continuous 30 passages along the inner surfaces of the ring sections 23 between the inlet and outlet ends of the machine.

In the machine illustrated, a plurality of rotor assemblies 25 are mounted in peripheral sets of four each for rotation with the hollow shaft 19. Each rotor assembly 35 includes a refining element 27 secured in a backing member 28 pivotally mounted to a collar 26 keyed to the shaft 19. The refining elements 25 are pivoted at their leading ends so that as the shaft 19 is rotated, the refining elements 27 are centrifugally urged against the abrasive liner 22. Both the liner rings 23 and the rotor elements 27 may be formed of stone, metal or of a synthetic ceramic of an abrasive type.

Means may be provided for maintaining a minimum clearance at all times between the surfaces of refining elements 27 and the abrasive surface of the liner rings 23, and such means may include push rods, such as indicated at 30, the radial position of which is controlled by respective frusto-conical wedge members such as 43 carried on respective telescoping rods such as 44 extending longitudinally inside the shaft 19. Means for adjusting the axial position of the rod 44 is illustrated in Figure 1 at 45, for example. The precise structure of the refining section of the machine is not per se a part of the present invention, and reference is made to my prior patents for such details, for example to my Patent No. 2,475,869 or 2,631,504.

For regulating the consistency of the stock fed into the refining section of the machine, means is provided at the inlet end of the machine for extracting a controlled amount of excess water from the stock. Such means includes impeller blades such as 50 (Figure 2) secured by bolts 51 to an annular plate 53, which is secured to the shaft 19. Said impeller blades are disposed between the inlet chamber 54 and the refining section of the machine defined by the shell 11. Referring to Figure 5, the arrow 55 indicates the direction of rotation of the impeller blades 50, and it will be observed that the leading inner marginal portion 56a adjacent the plate 53 is curved opposite to the direction of rotation of the blades so as to generally impel material radially outwardly toward peripheral notches such as 60 in the plate 53. The notches 60 afford communication between the inlet cham-

ber 54 and the refining section of the machine. The action of the impeller blades 50 tends to force material into the refining section of the machine and along the inner surfaces of the ring sections 23 to the outlet end of the machine.

Cooperating with the impeller blade 50 in removing excess liquid from the stock is a perforated ring 62 having apertures such as 63 therethrough leading from the inlet chamber to an annular chamber 65 formed in the inlet end plate 13. The ring 62 is secured to the end plate 13 by suitable means such as indicated at 66. A drain pipe 67 extends through the end plate 13 at the lower end thereof in communication with the drainage chamber 54 for delivering the liquid drained from the incoming stock to the outlet end of the machine, as will hereinafter be described.

As indicated in Figures 3 and 4, the openings 63 may be more or less uniformly distributed over the surface of the ring 62, and may be counterbored as indicated at 63a at the ends thereof remote from the inlet chamber to facilitate drainage. Also, as indicated in Figure 3, the axes of the openings 63 are inclined from a true radius opposite to the direction of rotation of the impeller blades 50, which is indicated by the arrow 70, in order to reduce the tendency of stock to plug the openings 63. The outer edges 50b of the impeller blades 50 are preferably machined to fit to a rather close tolerance within the ring 62 so as to tend to have a cleaning effect upon the surface of the ring. To the same end, the edges 50b are provided with a slight bevel away from the leading edge 50b as indicated at 50c (Figs. 5 and 6.)

For removing liquid from the drainage chamber 54 and for providing a very practical means for regulating the amount of liquid removed from the stock, a suitable variable speed pump 80 is connected with the drainage pipe 67 and may be driven by a suitable electric motor 81. A gate valve 82 may be interposed in the line 83 leading from the pipe 67 to the inlet to the pump 80 and the pump outlet may be connected by means of a line 85 to the outlet chamber of the machine defined by the dished outlet end plate 14 in a manner entirely similar to the inlet chamber defined by the inlet end plate 13. By regulating the flow of liquid through the pump 80, it is thus possible to control the amount of water removed from the stock in the inlet chamber.

Provision is made in the illustrated design to employ water under pressure to assist in cleaning out the openings 63 of the thickener should such be necessary, and to this end wash water under pressure from an outside source may be introduced into the pipe 87, with the gate valve 82 closed and hence through the lines 83 and 67 into the chamber 54. After passing through said openings 63, the water is discharged through an opening indicated at 90 (Fig. 2) at the top of the inlet plate 13.

The operation of the illustrated embodiment will now be understood. The stock or other fibrous suspension to be treated is introduced by means of the inlet pipe 16 into the inlet chamber. There, as the impeller blades 50 are rotated by means of the shaft 19, the material is forced against the perforated ring 62 by the action of centrifugal force. While the stock is in the process of being thickened, it is further somewhat compressed and moved laterally through the intake ports 60 in the plate 53 which feed the stock into the refining section of the machine ahead of the rotating refining elements 27. The stock is forced between the liner 22 and the refining elements 27 by the pressure head under which the material is delivered to the inlet 16 and by the action of the impeller blades. The amount of water removed from the stock mass at the inlet chamber is regulated by means of the pump 80 which removes liquid from the drainage chamber 54 and delivers it to the outlet chamber or at other suitable points where it is mixed with the stock discharged from the refining section of the machine.

As indicative of the improved properties that can be

imparted to the same stock as a result of refining the same at a higher consistency, such as can be obtainable by the use of my thickener and refiner, rather than that which is usual under normal operating conditions, the following

5 comparison is given of representative results in the refining of west coast bleached Kraft pulp at a moderately low consistency (4 to 5% on an air dry basis) and at a relatively high consistency (9 to 10% on an air dry basis). The rate of feed through the refiner used was in each case

10 2000 lbs. of bone dry stock per hour.

Comparison

Stock Consistency	Freeness	Mullen Strength, percent	Tear Factor	Fold
4 to 5% Before Refining-----	730	36.5	270	-----
4 to 5% After Refining-----	640	62.0	290	-----
9 to 10% Before Refining-----	725	35.1	274	16
9 to 10% After Refining-----	522	81.8	302	402

20 The improved Mullen strength tear factor, and fold qualities resulted solely from the use of the higher consistency, since the same stock was fed continuously at the same rate of feed, in the one case at the normal operating consistency of 4 to 5% through a rotary refiner not provided with my thickener feature but otherwise similar to that herein described, and in the other case at the same initial consistency or 4 to 5% through a combined thickener and refiner apparatus such as herein described and claimed. No auxiliary thickener ahead of my present rotary thickener and refiner was used; the stock consistency was raised to from 9 to 10% within the refiner itself by the action of the cooperating thickening elements of the device. The water so removed at 25 the feed end of the refiner was then returned for admixture with the refined stock discharged from the refiner.

30 Experience has proved that under normal operating conditions, excellent results are obtained in the refining 40 of chemical pulp screen rejects at 7-8% consistency, and of mechanical pulp screen rejects at 3.5 to 4% consistency, whereas if refined at normal consistencies of 1 to 2%, as delivered from the screens, the results are unsatisfactory.

35 45 I claim as my invention:

1. In a rotary refiner for wet fibrous material, a stationary shell having a cylindrical abrasive liner providing a refining surface, a drive shaft carrying centrifugally acting rotor elements having refining surfaces 50 for cooperating with said abrasive liner surface, inlet means 55 for cooperating with said shell to define an inlet chamber at one end thereof, outlet means cooperating with said shell to define an outlet chamber at the other end of said shell, means for introducing material into said inlet chamber, an impeller plate carried on said drive shaft and interposed between said inlet chamber and the refining section of the machine and having peripheral openings 60 therein affording communication from said inlet chamber to said refining section, impeller blades in said 60 inlet chamber and carried by said impeller plate for rotation therewith to impel the material in said inlet chamber toward the periphery thereof, and a ring secured about the periphery of said inlet chamber and having a plurality of openings for removing liquid expelled from 65 the material in said inlet chamber.

2. In a rotary refiner for wet fibrous material, a casing having a cylindrical abrasive liner providing an interior refining surface, a drive shaft mounted axially of said refining surface, centrifugally acting rotor elements carried by said shaft having refining surfaces for cooperating with said abrasive liner surface, said casing having an inlet chamber at one end thereof, an intermediate refining section and an outlet chamber at the opposite end thereof, means for introducing material 70 into said inlet chamber, impeller blades rotatable with

said drive shaft and disposed in said inlet chamber for impelling material in the inlet chamber toward the periphery thereof, means affording communication between the inlet chamber and the refining section of the machine, means disposed about the periphery of the inlet chamber and having openings therein for draining liquid from the material in said inlet chamber, said impeller blades extending in close relation to said drain means to tend to scrape material therefrom and expel liquid therethrough, said drain means comprising a ring having apertures therein, and the axis of said apertures being inclined opposite to the direction of movement of the impeller blade so as to avoid clogging thereof by the material in said inlet chamber.

3. In a rotary refiner for wet fibrous material, a casing having a cylindrical abrasive liner providing an interior refining surface, a drive shaft mounted axially of said refining surface, centrifugally acting rotor elements carried by said shaft having refining surfaces for cooperating with said abrasive liner surface, said casing having an inlet chamber at one end thereof, an intermediate refining section and an outlet chamber at the opposite end thereof, means for introducing material into said inlet chamber, impeller blades rotatable with said drive shaft and disposed in said inlet chamber for impelling material in the inlet chamber toward the periphery thereof, means affording communication between the inlet chamber and the refining section of the machine, means disposed about the periphery of the inlet chamber and having openings therein for draining liquid from the material in said inlet chamber, said impeller blades extending in close relation to said drain means to tend to scrape material therefrom and expel liquid therethrough, said drain means comprising a ring having a series of apertures therein, and said apertures being enlarged at the ends thereof remote from said inlet chamber to facilitate drainage of liquid therethrough.

4. In a rotary refiner for wet fibrous material, a casing having a cylindrical abrasive liner providing an interior refining surface, a drive shaft mounted axially of said refining surface, centrifugally acting rotor elements carried by said shaft having refining surfaces for cooperating with said abrasive liner surface, said casing having an inlet chamber at one end thereof, an intermediate refining section and an outlet chamber at the opposite end thereof, means for introducing material into said inlet chamber, impeller blades rotatable with said drive shaft and disposed in said inlet chamber for impelling material in the inlet chamber toward the periphery thereof, means affording communication between the inlet chamber and the refining section of the machine, and means disposed about the periphery of the inlet chamber and having openings therein for drain-

ing liquid from the material in said inlet chamber, the impeller blades being beveled at the outer edges thereof.

5. In a rotary refiner for wet fibrous material, a casing having a cylindrical abrasive liner providing an interior refining surface, a drive shaft mounted axially of said refining surface, centrifugally acting rotor elements carried by said shaft having refining surfaces for cooperating with said abrasive liner surface, said casing having an inlet chamber at one end thereof, an intermediate refining section and an outlet chamber at the opposite end thereof, means for introducing material into said inlet chamber, impeller blades rotatable with said drive shaft and disposed in said inlet chamber for impelling material in the inlet chamber toward the periphery thereof, means afford-
10 ing communication between the inlet chamber and the refining section of the machine, means disposed about the periphery of the inlet chamber and having openings there-
15 in for draining liquid from the material in said inlet chamber, and pump means for delivering liquid drained from the inlet chamber to said outlet chamber.

6. In a rotary refiner for wet fibrous material, a unitary casing having an inlet chamber at one end thereof, an intermediate refining section and an outlet chamber at the opposite end thereof, said casing having means pro-
20 viding a cylindrical abrasive liner in said intermediate refining section providing an interior refining surface, a drive shaft extending the length of said casing axially of said refining surface, centrifugally acting rotor elements carried by said shaft having refining surfaces for cooperat-
25 ing with said abrasive liner surface, means for introducing material into said inlet chamber, means defining a radially extending wall between said inlet chamber and said intermediate refining chamber having apertures providing axial communication between said inlet chamber and said in-
30 termediate chamber at the periphery of said inlet chamber, impeller blades disposed about said drive shaft in said inlet chamber for impelling material toward the periphery thereof, a perforated ring having a perforated portion thereof extending generally axially and defining the radially outer margin of said inlet chamber, and means controlling the pressure at the radially outer side of said ring outside of said inlet chamber to regulate the amount of water removed from said material in said inlet chamber.
